UNITED STATES PATENT OFFICE.

JOHN T. COWLES, OF CHICAGO, ILLINOIS, ASSIGNOR TO HIMSELF AND MATHIAS BENNER, OF SAME PLACE.

FIRE-ESCAPE LADDER.

SPECIFICATION forming part of Letters Patent No. 236,784, dated January 18, 1881.

Application filed December 15, 1879.

To all whom it may concern:

Be it known that I, JOHN T. COWLES, residing at Chicago, in the county of Cook and State of Illinois, and a citizen of the United States, have invented a new and useful Improvement in Fire-Escapes, of which the following is a full description, reference being had to the accompanying drawings, in which—

Figure 1 is a front elevation. Fig. 2 is a side elevation. Fig. 3 is a plan of the platform. Fig. 4 is a vertical section at *x* of Fig. 1. Fig. 5 is a section at line *x* of Fig. 3.

The steps used in ladders connected with stand-pipes are made of iron and have heretofore been round. In cold weather ice forms upon the rounds of the ladder and adheres thereto when the same is used, rendering it dangerous and difficult for firemen and others to ascend or descend the ladder.

The object of my invention is to so construct the steps of the ladders that, under ordinary conditions, the ice will be broken and removed by the action of the feet of persons using the same sufficiently to furnish a sure foothold; and this I accomplish by making the ladder-steps of such form that in use the feet will come in contact with a sharp edge, all as hereinafter more fully set forth.

In the drawings, *A* represents a stand-pipe, and *B* a ladder. As shown, one side, *a*, of the ladder is a bar or bars secured to the stand-pipe, and the other side, *b*, is a tube. *c* are the steps, which, as shown, are square, and are so placed in the side pieces, *a* *b*, that the feet of persons using the ladder will come in contact with a sharp edge, as shown in Figs. 1 and 4.

C is a platform, made of cast-iron or other suitable material, and having a number of openings of considerable size through the same, with the edges of the material around such openings made sharp, as shown in Fig. 5, so that the surface with which the feet come in contact in the use of the platform will present a series of sharp edges inclosing the openings, which edges, by the pressure or stamping of the feet thereon, will cut or break the ice as it accumulates on the platform into

pieces that will readily pass through the openings, or which can be thrown from the platform, and thereby keep the platform free or clear, and prevent the danger of slipping by presenting a firm hold for the feet. The sharp edges will be found of great assistance in the use of the platform when not covered with ice, as they will present a surface on which the feet cannot readily slip; but I make no claim to the construction of the platform, as it forms no part of my present invention.

D is the side of a building with which the stand-pipe, the ladder, and the platforms are connected in the usual or any suitable manner.

Under ordinary conditions, in case ice forms on the ladder-rounds, the weight of a person thereon will, in consequence of the sharp upper edges of the rounds, crush and break the ice under the feet, and the feet will come in contact with the sharp edge of the rounds, which furnish a safe foothold. So the weight of a person standing on the platform will break the ice upon the sharp edges of the bars of the platform and the broken ice will fall through the openings.

The advantages following from the use of ladders constructed as described are too obvious to require special mention.

The stand-pipe, ladder, and platforms are to be made of iron, as is usual, and the several parts are to be suitably connected together.

The use of the stand-pipe will be understood without specific description.

I do not claim, broadly, an angular round or rung for a ladder, as they have been heretofore used in wooden ladders of common construction and in common fire-escape ladders; but in all of these cases the rungs have been in line with the rails on two of their faces, and at right angles with the rails on the other two faces, so that the angle of the rungs, in use, depends entirely on the angle of the rails when the ladder is placed for use, which position seldom exceeds fifteen degrees from the vertical line, which leaves the rungs in use practically flat-topped, and in wood a sharp angle is so soon knocked off or worn off that they would be useless for my purpose; besides, my

stand-pipe is vertical and the rungs are set at an angle with the side supports, thus insuring the full effect of the angle or sharp edge at all times, thus giving them a difference in construction and operation.

What I claim as new, and desire to secure by Letters Patent, is as follows:

The vertical stand-pipe ladder constructed

as described, having the rungs set to present a sharp upper edge for breaking away accumulations of ice by simply using the ladder.

JOHN T. COWLES.
